United States Patent Office

Des. 186,488
Patented Oct. 27, 1959

186,488

ELECTRIC FOOT MASSAGER

Alfred W. Madl, Milwaukee, Wis., assignor to John Oster
Manufacturing Co., Milwaukee, Wis., a corporation of
Wisconsin

Application June 29, 1959, Serial No. 56,594

Term of patent 14 years

(Cl. D83—1)

Fig. 4.

Fig. 5.

Figure 1 is a front perspective view of an electric foot massager embodying my new design;

Figure 2 is a rear perspective view thereof;

Figure 3 is an elevational view as seen from the right side of Figure 1;

Figure 4 is a top plan view thereof; and

Figure 5 is a front elevational view of the electric foot massager.

The dominant features of my design reside in those portions thereof shown in full lines.

I claim:

The ornamental design for an electric foot massager, as shown and described.
